CONRAD PANTKE, OF NEW YORK, N. Y.

SPACE-COVERING STRUCTURE

Application filed March 6, 1929. Serial No. 344,730.

The present invention relates to improvements in space-covering structures, one object of the invention being the provision of a covering adapted for use upon tanks, silos and roofs of varying shapes, in which the covering supporting member is constructed in the form of a network or lattice, the elements of which are so connected that the stresses will arch around such members and, in the event of elimination or destruction of any portion of the arch due to fire or other causes, such stresses will be taken care of and the structure will be properly supported for a period of sufficient duration to permit of the repair and replacement of the defective or eliminated portions of the structure.

Another object of the invention is the provision of a network roofing frame, the elements of which may be constructed at the mill and shipped ready for erection, the elements being readily assembled at the building site in a simple manner without the use of trusses, beams or the like, and with employment of a minimum amount of light scaffolding.

Still another object of the invention is the provision of elements formed of any suitable material, such as wood, steel or reinforced concrete, which elements may be curved or straight and bent at one or more points in their length, said elements each being longer than their width and wider than their thickness in order to accomplish the main object of the present invention.

Still another object of this invention is the provision of elements for forming a roof structure which are easily and readily distinguishable from structural members ordinarily used by reason of the fact that they are provided at their ends with parts which project essentially and approximately in the direction of their width, these parts serving as a convenient point for simple and economical connection for producing the final network structure.

With the foregoing and other objects in view, which will appear as the description proceeds, the invention resides in the combination and arrangements of parts and in the details of construction hereinafter described and claimed, it being understood that changes

in the precise embodiment of the invention herein disclosed can be made within the scope of what is claimed without departing from the spirit of the invention.

In the drawings:—

Figure 1 is a diagrammatic view of an oval-shaped covering structure made according to and embodying the present invention;

Figure 2 is a section taken on line 2—2 of Figure 1;

Figure 3 is a section taken on line 3—3 of Figure 1;

Figure 4 is a view similar to Figure 1 of a circular domed type of covering;

Figure 5 is a section taken on line 5—5 of Figure 4;

Figure 6 is a view similar to Figures 1 and 4 of a rectangular domed structure made according to and embodying the present invention;

Figure 7 is a section taken on line 7—7 of Figure 6;

Figure 8 is a section taken on line 8—8 of Figure 6;

Figure 9 is a top plan view of one type of joint or connection used in forming any of the roof structures previously illustrated;

Figure 10 is a view similar to Figure 9 of a form of joint;

Figure 11 is a view similar to Figures 9 and 10 of still another modified form of joint;

Figure 12 is an end view of the joint shown in Figure 11 but which basically illustrates the joints shown in Figures 9 and 10;

Figure 13 is a plan view of still another modified form of joint;

Figure 14 is an end view of the joint of Figure 13;

Figure 15 is a view similar to Figure 9 of still another modified form of joint;

Figure 16 is an end view of the joint shown in Figure 15;

Figure 17 is a top plan view of a portion of a truss covering made according to and embodying the present invention;

Figure 18 is a section taken on line 18—18 of Figure 17;

Figure 19 is an enlarged detail sectional view of the wall and adjacent portion of the covering as shown in Figure 17; and

Figure 20 is a top plan view of the portion of the covering shown in Figure 19, the wall being omitted.

Referring to the drawings and more particularly to the structures shown in Figures 1 to 16, inclusive, the elements 21, in Figures 1, 4 and 6, constitute the outer frame portion of the respective structures. Connected to and extending throughout the structure are the various joints 22, the details of which are clearly illustrated in Figures 9 to 16, inclusive, and which may be slightly modified to produce the necessary contour for the outer surface of the roof structure, as particularly illustrated in the cross-sections of the several views.

In the structure illustrated in Figure 9, a breast plate 23 and connecting elements 24 and 25 are employed, the elements 24 being connected to the angle plates 26, the upstanding portions 27 of which are connected to the plate 23, while the elements 25 are connected to the angle members 28, the upstanding portions 29 of which abut the opposite sides of the plates 23 and are attached thereto with the upstanding portions 27 of the angle plates 26 by means of the bolts 30. An angle plate 33 is also attached to the plate 23 centrally therof, and between the angle plates 28, and by means of the rivets 32 the elements 31 are attached thereto. By this means, the upper faces of the elements 24 and 25 may be so positioned with relation to the attaching plates 26 and 28 that the desired angularity may be imparted thereto to produce the contour necessary for the covering.

As shown in Fig. 10, the plate 23' is shorter than the plate 23 illustrated in Figure 9, and the plate 33 is dispensed with, the elements corresponding to the elements in Figure 9 being primed, the only difference in structure being that the elements 31' are attached to the respective plates 28' instead of to an additional plate, as illustrated in Figure 9.

In Figure 11 the parts corresponding to those illustrated in Figure 9 are double primed, the plate 23'' being disposed at a right angle to that shown in Figures 9 and 10, while the angle plates 26'' and 28'' are also parallel to the elements 31'' instead of at right angles thereto.

The joint as shown in Figure 12 may be taken as typical of the several joints, but this figure is an elevational view of Figure 11, the angularity of the elements 24'' and 25'' with the attaching bolts 35 securing the elements 31'' in position upon opposite sides of the plate 23'' being illustrated therein.

As shown in Figure 13, the elements which correspond to those shown in Figure 9 are designated by corresponding reference numerals with the addition of the exponent "a", the plate which corresponds to the plate 23 in Figure 9 being placed in a similar position and designated 23^a, and the parts being illus-

trated in side elevation in Figure 14. In these figures the two oppositely disposed pairs of angle irons 37 and 39 are shown as connected together by means of the bolts 41 and 42 and properly support the angle irons 26^a and 28^a so that the elements 24^a and 25^a are supported at the desired inclination or angularity.

In Figures 15 and 16, the parts corresponding to those illustrated in Figure 9 are designated by reference numerals with the addition of the exponent "b", this structure producing a slightly different angle and positioning of the elements 24^b and 25^b.

By combining the respective joints illustrated in Figures 9 to 16, and also certain modifications thereof, the connecting elements 24, 25 and 31, which are longer than they are wide, and wider than they are thick, in all instances, are properly connected so as to produce the several structures as illustrated in Figures 1, 4 and 6, to the end that the various shapes and a section, as illustrated in the other views, may be imparted to the covering to produce a net-like arrangement.

It will thus be seen that, when these various joints and elements are assembled, they provide a safe structure, which even though certain members may be eliminated or destroyed due to fire, or other causes, will stand up safely, inasmuch as the stresses will arch around the space previously occupied by such eliminated members. Thus, if a section were eliminated from any one of the structures illustrated, the surrounding elements and their joints would take care of these stresses previously supported by the eliminated section and thus prevent sagging or collapsing of the covering structure.

In Figures 17 to 20, inclusive, a slightly modified form of covering R is shown. In this instance, the walls 43 are provided upon their inner faces with a recessed portion 44 for the reception of anchoring plates 45 and metal anchors 46. Attached to each plate 45 of some of the oppositely disposed pairs of plates 45 by the upper ends of said anchors is an angle plate 47 to which a tie-rod 48 with its supporting strut 48' is properly attached for the purpose of bracing the covering R. This covering comprises a number of elements E, each one of which is typical, but where attached to the wall consist of the two upright angle plates 49 spaced apart and attached to the elements 50. These elements 50 are provided with angle strips 51, one above and one below, and extending the full length of the wall, while attached to the outer face of these angle strips is a plate 23^c similar to the plate 23, illustrated in Figure 9, and which constitutes the anchoring plate for the angle strips 51 and the angle plates 53 to which the elements 54 are attached. Thus it will be seen that with the present structure the primary object of producing elements of greater

length than width and of greater width than thickness is attained in the production of an arched structure of the same segmental or arch shape throughout its length and especially adapted for use upon hangers and buildings of a like nature.

From the foregoing description, considered in connection with the drawings, it will be evident that with this lattice or network construction of covering, a roof of any desired contour, deformed, regular or irregular, may be constructed, and that the elements constituting the same may be manufactured at the mill according to drawings, or the like, and be shipped ready for erection; that the same may be erected with the use of exceedingly light scaffolding and without the employment of cranes; that the joints and connecting elements may be so arranged in sets as to provide a rigid frame for supporting any type of roof covering; and, where desired, glass or transparent elements may be employed for the admission of light to the building.

It will also be apparent that, in the event of the elimination of some of the members 24 and 25 and the joints connecting the same, the present type of covering will stand up safely inasmuch as the stresses can and will arch around the positions formerly occupied by the members which have been eliminated.

It will also be apparent that this construction of covering frame may be repaired or replaced in much the same fashion as a hole in a fishing net is mended; that is to say, by the introduction of new elements 24 and 25 and their connecting members.

It is to be understood that these structures may form either a shell closed in itself, or any part of a shell, such as a segment or zone, or a combination of parts of different shells. These shells may or may not be covered on the inside or outside, or on both sides, and the joints may or may not be tied together or braced against each other by additional means such as ties, braces, struts or the like, and that other elements or systems of elements may be superimposed upon the shells.

I claim:—

1. In a self-supporting lattice, net-like arranged flanged elements of greater length than width and greater width than thickness, angle clips, said clips each having one flange attached to a flange of an adjacent element, the other flanges of the angle clips protruding in the direction of the width of said elements, a plate between adjacent protruding clip flanges, and means for connecting the said clip flanges and plates.

2. In a self-supporting lattice, net-like arranged flanged elements of greater length than width and greater width than thickness, angle clips, said clips each having one flange attached to a flange of an adjacent element, the other flanges of the angle clips protruding in the direction of the width of said ele-

ments, a plate disposed between the ends of adjacent flanged elements and between adjacent protruding clip flanges, and means for connecting the said clip flanges and plates.

3. In a self-supporting lattice, net-like arranged flanged elements of greater length than width and greater width than thickness, angle clips arranged in pluralities substantially laterally of the lattice, said clips each having one flange attached to a flange of an adjacent element, the other flanges of the angle clips protruding in the direction of the width of said elements, a plate between adjacent pluralities of the protruding clip flanges, and means for connecting the said clip flanges and plates.

4. In a self-supporting lattice, net-like arranged flanged elements of greater length than width and greater width than thickness, angle clips, bolts securing one flange of each clip to an adjacent element, the other flanges of the angle clips protruding in the direction of the width of said elements, a plate between adjacent protruding clip flanges, and bolts connecting the said clip flanges and plates.

In testimony whereof I have hereunto set my hand.

CONRAD PANTKE.
